(57) **CLAIM**

The ornamental design for a bracket for skateboard light as shown and described.

DESCRIPTION

FIG. 1 is a top perspective view of a bracket for skateboard light showing my new design;

FIG. 2 is a bottom perspective view thereof;

FIG. 3 is a front elevational view, wherein the rear elevational view is a mirror image thereof;

FIG. 4 is a left side view, wherein the right side view is a mirror image thereof;

FIG. 5 is a top plan view thereof;

FIG. 6 is a bottom plan view thereof;

FIG. 7 is a top perspective view of the bracket for skateboard light in a detached state;

FIG. 8 is a bottom perspective view of the bracket for skateboard light in a detached state;

FIG. 9 is a top perspective view of the bracket for skateboard light in a detached state in a using environment;

FIG. 10 is a bottom perspective view of the bracket for skateboard light in a detached state in a using environment;

FIG. 11 is a top perspective view of the first piece of the bracket for skateboard light;

FIG. 12 is a bottom perspective view of the first piece thereof;

FIG. 13 is a front elevational view of the first piece, wherein the rear elevational view is a mirror image thereof;

FIG. 14 is a left side view of the first piece, wherein the right side view is a mirror image thereof;

FIG. 15 is a top plan view of the first piece thereof;

FIG. 16 is a bottom plan view of the first piece thereof;

FIG. 17 is a top perspective view of the second piece thereof;

FIG. 18 is a bottom perspective view of the second piece thereof;

FIG. 19 is a front elevational view of the second piece, wherein the rear elevational view is a mirror image thereof;

FIG. 20 is a left side view of the second piece, wherein the right side view is a mirror image thereof;

FIG. 21 is a top plan view of the second piece thereof; and,

FIG. 22 is a bottom plan view of the second piece thereof.

The broken lines in the figures are for the purposes of illustrating portions of the bracket for skateboard light, the broken lines in the FIG. 9 and FIG. 10 are directed to environment, all broken lines form no part of the claim design.

1 Claim, 13 Drawing Sheets
